United States Patent

[19]

Apps et al.**Patent Number: Des. 410,778****Date of Patent: ** Jun. 8, 1999**[54] **COMPARTMENT STRUCTURE OF BOTTLE CASE**[75] Inventors: **William P. Apps**, Alpharetta; **Gerald R. Koefeda**, Atlanta, both of Ga.[73] Assignee: **Rehrig Pacific Company**, Los Angeles, Calif.[**] Term: **14 Years**[21] Appl. No.: **29/081,729**[22] Filed: **Jan. 8, 1998****Related U.S. Application Data**

[62] Division of application No. 29/067,185, Feb. 28, 1997, Pat. No. Des. 395,954, which is a division of application No. 29/039,952, Jun. 7, 1995, Pat. No. Des. 378,249, which is a continuation-in-part of application No. 29/037,469, Apr. 13, 1995, Pat. No. Des. 380,901, which is a continuation-in-part of application No. 29/018,317, Feb. 3, 1994, Pat. No. Des. 361,431, and application No. 29/034,317, Feb. 1, 1995, Pat. No. Des. 379,717, which is a continuation-in-part of application No. 07/919,376, Jul. 29, 1992, Pat. No. 5,529,176.

OTHER PUBLICATIONS

Exhibits A & B: Two photos of an embodiment of U.S. Pat. No. 4,773,554 to Warwick.

Exhibits D-F: Three photos of a bottle neck resting type crate with projections above the outer side walls.

Exhibits G-J: Four photos of bottle neck resting type crate without projections above the outer side walls.

Exhibits K: One photo of a bottle neck resting type crate with different height outer side walls.

Exhibits L: Four photos of an embodiment of Great Britain Patent Publication No. 2,158,044 & U.S. Design Patent No. D289,938.

(List continued on next page.)

Primary Examiner—Ted Shooman*Assistant Examiner*—Adir Aronovich*Attorney, Agent, or Firm*—Banner & Witcoff, Ltd.**[57] CLAIM**

The ornamental design for a compartment structure of bottle case, as shown and described.

DESCRIPTION

FIG. 1 is a top perspective view of a compartment structure of a bottle case showing our new design;

FIG. 2 is a top plan thereof; and,

FIG. 3 is a bottom plan view thereof.

The broken lines depict environmental structure which forms no part of the claimed design.
